UNITED STATES PATENT OFFICE.

JOHN P. MALLETT AND THOMAS E. DROHAN, OF MADISON, WISCONSIN, AS-SIGNORS TO NORTHERN ELECTRICAL MANUFACTURING COMPANY, OF MADISON, WISCONSIN, A CORPORATION OF WISCONSIN.

BRUSH-HOLDER.

No. 850,237.

Specification of Letters Patent.

Patented April 16, 1907.

Application filed May 10, 1901. Serial No. 59,557.

To all whom it may concern:

Be it known that we, JOHN P. MALLETT and THOMAS E. DROHAN, citizens of the United States, both residing at Madison, in the county of Dane and State of Wisconsin, have invented a certain new and useful Improvement in Brush-Holders, of which the following is a specification.

Our invention relates to brush-holders, and has for its object to provide a new and improved brush-holder to be used in connection with dynamos, motors, and other electrical appliances.

Our invention is illustrated in the accompanying drawings, wherein—

Figure 1 is a side view of a brush embodying our invention. Fig. 2 is a vertical longitudinal section through the brush shown in Fig. 1. Fig. 3 is a plan view showing one section of the brush.

Like letters refer to like parts throughout the several figures.

Referring now to the drawings, we provide a frame A, preferably of metal, to which the brush B of any desired material is connected.

We have shown the brush as a carbon brush. The brush may be connected to the frame in any desired manner, and, as herein shown, the connection is made by means of a screw 30 C, which passes through the brush and enters the frame. The frame A is movably mounted upon the rod or stud D, which is supported in any desired manner, so as to hold the brush in proper relation to the commutator 35 E. An engaging part or member F is located between the arms of the frame A. This engaging part is tightly clamped in any desired manner to the stud D, so as to make good electrical contact therewith, and is provided

40 with a projecting part extending between the sides of the frame A toward the brush B. As herein shown, the end of the engaging part is split, and it is clamped in position by means of the thumb-screw G. A pressure-regulating spring H is mounted in the frame A and has one end rigidly connected with the frame in any desired manner, as by means of the screw I. This spring is bent back upon itself, and the other end makes contact with the engaging part F at the point J. The spring preferably passes around the cross-piece or holding part K, which prevents the loop end from becoming displaced. This spring, as

herein shown, is U-shaped, and the pressure of the brush or other contact on the opposed contact may be regulated by varying the position of the stud D or of the engaging part F. The engaging part F is electrically connected with the brush B and the frame A by means of the flexible connection L, which 60 may be a spring or other flexible device, as desired. It will thus be seen that by this construction a brush is provided which is elastically forced against the commutator or other opposed part, in which the electrical 65 connections are positive, there being no sliding contacts. The construction is such that the major portion of the spring is located between the arms of the frame. By reason of the proximity of the said arms to the spring 70 the latter is practically inclosed and protected by the frame. It will also be seen that we have here a construction for effectively securing the tension of the brush on the commutator and for adjusting said tension for 75 carrying off the current from the brush to the terminals and for also preventing injury to the commutator by contact with the frame. The construction disclosed permits the use of a relatively long spring, which is so disposed 80 as to take up but little room.

The current passes from the brush to the flexible connection L, thence to the engaging part F, and thence to the stud D, all of the contacts between the various parts being 85 fixed or stationary, so that an efficient electrical contact is obtained. The brush-holder is provided with a protecting device for the commutator, arranged so that the frame of the holder cannot come in contact 90 with the commutator when the brush becomes worn. As herein illustrated, this result is obtained by fastening an insulating-piece M to the lower part of the frame. When the brush becomes worn a predetermined 95 amount, this insulating-piece rests on the commutator and prevents the frame of the holder from cutting or otherwise injuring it. The frame A may be made of any desired material, and to secure a light brush-holder we 100 prefer to construct it of aluminium.

In Fig. 3 we have shown one section of the brush, and it will be understood that in most instances two or more of these sections are used side by side and mounted upon the same 105 stud.

We have described in detail a particular construction embodying our invention; but it is of course evident that the parts may be varied in many particulars without departing 5 from the spirit of our invention. We therefore do not limit ourselves to the construction shown.

We claim—

1. A brush-holder, comprising a frame, a brush rigidly connected with said frame, an engaging part associated with the frame and rigidly connected with a support, a spring bent back upon itself and interposed between the engaging part and the frame, so that the 15 brush will be elastically forced against its opposed surface when the engaging device is properly adjusted, and a flexible connection between the brush and the engaging device and having a stationary contact with each.
2. A brush-holder, comprising a frame movably mounted on a support and to which the brush is rigidly connected, an engaging part rigidly connected to the support and associated with said frame, a U-shaped spring 25 fixed at one end to the frame and passing around a holding part on the engaging part, the other end of said spring loosely engaging the engaging part, and a flexible electrical connection between the engaging part and 30 the brush.
3. A brush-holder, comprising a frame movably mounted on a support and to which the brush is rigidly connected, an engaging part rigidly connected to the support and associated with said frame, a U-shaped spring 35 fixed at one end to the frame and passing around a holding part on the engaging part, the other end of said spring loosely engaging the engaging part, a flexible electrical connection between the engaging part and the brush, and an insulating piece connected with said frame, so as to limit the movement 40 of the frame toward the commutator when the brush becomes worn a predetermined amount.
4. A brush-holder comprising a frame to which the brush is rigidly connected, a stud upon which said frame is movably mounted, an engaging part rigidly connected with said 45 stud, a spring interposed between the engaging part and the frame, a flexible connection between said engaging part and the brush and a protecting device mounted upon said frame for preventing the frame from engaging the commutator.
5. A brush-supporting device comprising a brush-carrying frame formed with two side pieces spaced apart, a stud upon which said frame is movably mounted, an engaging 50 member rigidly connected to said stud and formed with the projecting part extending between the side pieces of the frame, and a U-shaped spring, one end of said spring engaging the projecting part of said member 55 and the other end of said spring engaging the

frame while the body of said spring is located between the side pieces of said frame.

6. A brush-holder comprising a brush-carrying frame movably mounted on a support, a member rigidly connected to the support 7c and provided with a holding part and a U-shaped spring looped around the holding part of the member, one end of said spring engaging said member and the other end of said spring engaging said frame. 75

7. In a brush-supporting device, a stud, a brush-carrying frame loosely mounted thereon, a member rigidly secured to the stud and extending between the arms of the frame, and an elongated U-shaped spring also located between the arms of the frame with one end engaging the frame and the other end engaging said member. 80

8. In combination, a movable frame adapted to carry a brush at one of its ends, a fixed 85 member located between the arms of said frame, and a U-shaped spring the legs of which extend substantially parallel to and between the arms of said frame, one end of said spring engaging said member and the other end of said spring engaging said frame. 90

9. In a brush-supporting device, a stud, a brush-carrying frame loosely mounted thereon, a member rigidly secured to the stud and extending between the arms of the frame, 95 and an elongated U-shaped spring located between, and with its legs parallel to, the arms of the frame with its bowed portion adjacent the stud and with one end engaging the frame and the other end engaging said member. 100

10. In a brush-holder, a movable brush-carrying frame, means for pressing said frame toward the commutator and a protective device carried by said frame in position to limit the movement of said frame toward 105 said commutator by reason of the engagement of the device with the commutator.

11. In a brush-supporting device, a stud, a brush-carrying frame comprising two arms the ends of which are loosely mounted on 110 said stud, a member rigidly secured to the stud and extending between the arms of the frame, and an elongated U-shaped spring also located between the arms of the frame with one end engaging the frame and the other end engaging said member, the yoke of 115 said spring being adjacent the stud and the ends adjacent to the brush.

12. In a brush-holder, a metallic frame, and a non-metallic protective device carried thereby in a position to prevent engagement between the frame and the commutator by reason of its interposition between them. 120

13. In a brush-holder, a movable metallic brush-carrying frame and a non-metallic protecting device carried by the frame in position to engage the commutator to prevent the frame from coming into contact with the commutator. 125

14. In a brush-holder, the combination 130

with a pivot-shaft, of a brush-supporting frame pivoted thereto, a brush rigidly secured to said frame, spring means engaging said frame to hold the brush against the commutator with which the brush-holder is associated, and a block of insulating material for engaging the commutator as the brush wears down to prevent engagement

of the commutator with the metallic brush-frame.
